UNITED STATES PATENT OFFICE

ERIC A. HOLMGREN, OF LYNN, MASSACHUSETTS, ASSIGNOR TO UNITED SHOE MACHINERY CORPORATION, OF PATERSON, NEW JERSEY, A CORPORATION OF NEW JERSEY

ASSEMBLING MACHINE

Application filed April 13, 1925. Serial No. 22,624.

The present invention relates to assembling machines, being especially directed to that type of apparatus disclosed in Letters Patent of the United States No. 1,667,948, Perry, 5 May, 1, 1928, for a machine for making soles. By this machine, a plurality of portions of the insole of a shoe, as a layer of fabric and a layer of leather or a substitute therefor, are taken from their respective holders; the 10 fabric first transferred to such forming means as dies, which produce upon it a sewing rib; and then the leather portion coated with an adhesive, transferred to the formed canvas, and the two portions pressed together to 15 give a complete insole. The purpose of my invention is to generally improve apparatus of this character, though it will be evident that many of its features are by no means limited to insole-making machines.

20 A feature of my invention is found in the means by which the work-portions are transferred from their holders to the means which is to operate upon them. Mechanisms are provided which are simple, certain in action, 25 accurate as to delivery, and which may readily be adjusted to act upon work of different size.

Another feature of the invention involves the freeing of the assembled work from the 30 pressure members which operate upon it, to prepare for discharge from the machine, the support of the work after it has been thus freed, and its final ejection.

A further feature of my invention has to 35 do with the operation upon the work-portions, as the application of the forming and assembling pressure thereto. The duration of such pressure is controlled independently of the action of other instrumentalities under 40 the influence of which the work comes, so no delay or other irregularity is introduced into the general operation of the machine. Preferably, means which automatically controls the time during which pressure is applied is 45 stopped for a variable period to lengthen or shorten the duration of the operation.

Other features of my invention will appear 50 from the following description and be pointed out in the appended claims. The work-holder employed for the fabric portions and

the disconnecting or time-controlling mechanism per se, both disclosed herein, are respectively made the subjects of divisional applications filed May 7, 1930, Serial No. 450,537, and filed May 13, 1930, Serial No. 451,934. 55

As to its general organization, this machine 10 is similar to that of the previously mentioned patent. A turret 25, rotatable about a vertical axis upon a frame 26 and best shown in Figs. 1 and 2 of the drawings, carries four lower combined rib-forming and assembling 15 dies 27 successively separated about the turret by angles of 90 degrees and having their work-receiving faces in substantially horizontal planes. Arranged to reciprocate vertically upon the frame above the turret are 20 four dies for co-operation with the dies 27, one pair 28, 28 being for the purpose of forming ribs in fabric portions which are included in the soles, while a pair 29, 29 act to press the thus formed elements and leather portions 25 together to complete the soles. All the dies are so mounted that they may be changed to correspond to the size of the soles to be produced. The dies 28, 28 are situated at work- 30 stations A and B, and are of such contour as to operate, respectively, upon right and left soles. The dies 29, 29 are located at stations C and D, and are similarly arranged for the formation of the respective soles of a pair. The corresponding dies, that is, the rights 35 and lefts of the two pairs, are separated from each other by 180 degrees, those of each pair being 90 degrees apart. The co-operating dies 27 are in a like manner arranged in pairs of rights and lefts. Carried at the lower portion 40 of the frame is a motor 30, shown in the present instance as electric, which supplies power through clutch mechanism 32 controlled by cam mechanism 34 to alternately rotate the turret through 180 degrees, so that 45 the pairs of dies 27, consisting of a right and a left, are successively presented at stations A, B and C, D for co-operation with the dies 28 and 29, and to reciprocate these last-mentioned dies to produce their forming and assembling effects. When the turret is in motion, the upper dies are at rest, and when the travel of the turret ceases, the reciprocation of the upper dies takes place. The upper 50 section of the clutch mechanism is geared to the turret at 36 to produce its intermittent rotation, while the lower clutch-section operates, through gearing 37 and a central shaft 38, crank mechanisms 40, which intermittently reciprocate together the dies 28 and 29. 55 The last-mentioned connections are through a mechanism X (Fig. 4), which will later be described. Now it need only be said that this mechanism X serves to control the time during which the dies 28 and 29 are forced 60 against the work upon the dies 27. Each

operating station of the machine is provided with means for supplying the pair of dies there positioned with a portion which goes to make up the completed sole. At stations A and B, pieces F of canvas or other fabric 70 are simultaneously fed, and at stations C and D, blanks L of leather or a leather substitute carrying a coating of an adhesive are delivered to the previously received and formed canvas portions for assembly therewith. The supplying mechanism at stations A and B, and C and D, respectively, perform the same functions and may be identical. Therefore, but one will be described in each instance. 75

Considering the fabric-holding and feeding means, and referring particularly to Figs. 6 to 9, inclusive, there is supported at each of the stations A and B, upon a bracket 41 projecting from the main frame, a skeleton magazine-frame 42. Situated axially of the magazine and fixed in the frame below it is a vertical guide-rod 44, about which moves a sleeve 46 having fixed upon its upper extremity a platform 47 for the support of the fabric work-portions F arranged in a stack. The platform, the parts which carry it, and the supported material are counterbalanced by a weight 48, which is hung upon a cord 50 wound about a sheave 52 90 rotatable upon the bracket 41. The opposite end of the cord is attached to an arm 49 clamped on the sleeve 46 and sliding upon a vertical rod 51 secured to the frame. Rotatable with the sheave is a ratchet-wheel 54, 95 with which co-operates a spring-actuated detent 56, holding the platform and stack against downward movement. To position the top of the stack at the desired level as the work-pieces are removed therefrom, elevating mechanism is provided, actuated with a mechanism T, which effects the transfer of the blanks from the magazine to the dies 27. The elevating mechanism includes a pawl 58 100 engaging the teeth of the wheel 54 and pivoted upon a lever 60 fulcrumed upon the frame and forked to engage a sleeve 62 of the transferring mechanism, this sleeve being arranged for reciprocation upon the rod 51. Movement of the sleeve occurs each time 105 a piece is transferred from the magazine to the dies; and at the same time, through the lever 60, pawl 58 and ratchet 54, the sheave is turned to lift the platform 47 through a pre-determined distance. The extent of this feed is somewhat more than the thickness of one of the fabric pieces, so that the transferring instrumentality may always find the element which it is to engage somewhat above 110 the level to which the transferring mechanism descends and therefore in position to receive firm contact. This excess of engaging movement of the transfer mechanism is permitted by frictional connections between the ratchet-wheel and the sheave. The former 115

has a sleeve 64 (Fig. 7) turning upon a spindle 66 projecting from the bracket 41, the adjacent faces of the sheave and ratchet engaging frictionally. At the opposite end of the sheave is a thrust-bearing 68, against the outer side of which acts a spring-washer 70, this, in turn, abutting against a split nut 72 clamped upon the sleeve. A nut and washer 74 upon the outer extremity of the spindle 66 hold all these co-operating elements against displacement. The force exerted by the washer 70 is sufficient to cause the ratchet and sheave to normally rotate together. When, however, the platform is held against movement by the detent 56 and the transfer mechanism engages the top piece F upon the stack supported upon the platform, the sheave will yield under the pressure, yet offering such resistance as to insure firm contact between the work-portion and the element engaging it. Fixed to turn adjustably below the pawl 58 is a stop-sleeve 75. This has an eccentric or flattened portion, over which the pawl moves without interference. If it is desired to check the upward feed of the fabric without stopping the other elements of the machine, this sleeve may be turned until its rounded portion comes opposite the pawl, lifting this from the ratchet-wheel so that, in the reciprocation of the pawl, said ratchet-wheel will not be operated, and the platform will remain at rest. This is of utility in testing and adjusting the apparatus, or upon completing the operation at the end of a period of use. To maintain the effect of the weight 48 in a substantially constant relation to the opposing force exerted by the stack of pieces F, as this varies with the number of pieces upon the platform, a compensating device is associated with the counterbalance. This is furnished by the form of the sheave, which has a spiral, stepped groove 76 for engagement by the turns of the cord 50 wound about it. The steps are of greatest diameter at the ends of the sheave, and least at the center. When the stack is at its maximum height, and therefore heaviest, the extremity of the cord bearing the weight will be at the outer portion of the sheave upon the highest step, while the extremity of the cord connected to the platform will be near the center of said sheave. As the platform rises and the weight falls, the relation will be reversed, the weight-end of the cord descending the incline, and the platform-end rising at the opposite side. In this way, the leverage exerted is gradually oppositely varied, so that the effect of the weight is diminished and increased proportionately to the number of work-pieces upon the platform. Therefore, the normal force which the frictional device between the sheave and ratchet is called upon to resist is kept substantially constant.

65 The work-portions F, which may be of dif-

ferent sizes, corresponding to those of the soles into which they are to enter, are correctly positioned in the magazines at stations A and B by vertical contact-rods extending the entire height of the magazines and arranged in pairs 78, 78 and 80, 80, these pairs being, respectively, at opposite sides and near the extremities of the heel and toe-portions. The rods are carried upon arms 81 pivoted at 82 upon the magazine-frame 42, and are arranged to be moved together by a linkage 84 so proportioned that the shift in the position of one of the rods 78 will similarly move the companion heel-rod, while the toe-rods 80 will have their positions altered correspondingly. The settings of the rods are determined and maintained by a finger-lever 86 secured to turn with one of the arms 81 and having a spring-pressed detent 88 engaging any one of a series of notches 90 in a segmental plate 92 mounted upon the lower portion of the magazine-frame. Associated with the notches are sole-size designations, indicating the settings of the rods to give the correct positioning of the work-pieces in the magazine. This movement of the lever 86, by a proper proportioning of the arms and connections, gives a simultaneous adjustment of all the rods for each size of sole which is to be produced, and therefore for the dies employed.

To transfer the work-portions one by one from the magazines at stations A and B to the dies 27, which, at the time, have been brought by the turret to these stations, I prefer to employ pneumatic mechanism T (Fig. 9). Upon each sleeve 62 is carried a horizontally extending hollow arm 100, at the outer end of which is a contact-head 102 having in its under side three spaced openings 104. These openings are so related that they will co-operate with the fabric pieces F in the stack over areas extending transversely near the center and in proximity to the opposite ends. Into the arm opens a conduit 106, through which a suction is maintained. This conduit is preferably flexible, to permit movement of the arm 100, and includes a swiveled joint 108, which also facilitates this. The suction-head has imparted to it vertical movement into and out of co-operation with the top of the stack in the magazine, to engage and remove the terminal work-piece, and a corresponding movement into proximity with the die, to deposit the piece thereon, and then from the die preparatory to return to the magazine. It is also oscillated horizontally to effect such transfer from the magazine to the die, and the return for the succeeding operation. To raise and lower the head, the groove in the sleeve 62, which is engaged by the lever 60, also receives the forked end of a bell-crank-lever 110 fulcrumed upon an extension from the bracket 41. The other arm of the lever 110 is joined by a connecting-rod 130

112 to a lever 114 pivoted for horizontal movement and having a projection 115 entering a cam-groove in a rotatable disk 116. The connections to the lever 114 extend to both stations A and B, to simultaneously actuate the transfer mechanisms T thereat. The disk 116 is fast upon the upper extremity of a shaft 118, which includes an inclined section, and which is geared at 120 (Fig. 4) to a horizontal shaft 122 journaled in the lower portion of the frame 26. The shaft 122 is rotated through the timing mechanism X. The suction-head is turned about its vertical axis through a gear-segment 124 fixed upon the sleeve 62 and having meshing with it a rack 126, sliding upon the magazine-support and joined by a rod 128 to a bell-crank-lever 130 acting upon the transfer mechanisms of both stations A and B. A projection 131 from the lever 130 enters a cam-groove in the upper face of the disk 116. The relation between the cam and the connecting mechanisms, which respectively raise and lower and turn each suction-head, is such that said head is swung horizontally from the turret to the magazine; then depressed until it contacts with the top piece of fabric; raised to its former position; again turned until it is over the die 27 then at the station; lowered to deliver the transferred piece to the die; and raised and returned for another transferring cycle.

For the purpose of temporarily holding the work-portions against the openings 104 of each head 102 for their elevation from the stack, their transfer and final release upon a die 27, the passage of air through the openings is controlled by valve mechanism actuated in the movement of the head. In the conduit 106, at its junction with the head, is a slot in which operates a valve-plate 132 mounted to oscillate upon a pivot 134. Adjacent to the conduit-connection, the head has a relief-opening 136. The plate 132 has two lobes, in one of which is an opening 138, while the other is imperforate. When the opening 138 is alined with the conduit, so that this is in communication with the head 102, the relief-opening 136 is closed by the plate. When said plate is swung in the opposite direction upon its pivot, the imperforate portion moves between the conduit and the opening in the arm to close this, simultaneously freeing the relief-opening. Secured upon the pivot 134 is a small plate 140, slotted at its edge to furnish opposite contact-faces 142, 142, which, in the movement of the plate 132, may strike a pin 144 projecting from the arm 100. The extremes of movement of the valve-plate, as has just been described, are determined by these contacts. A spring 146, extending between an arm 148 fixed to the pivot and the arm 100, acts to hold either of the contact-faces 142 against the pin. Upon the opposite extremities of

the plate 140 are contact-projections 150, 152. When the head 102 is over the magazine, the projection 150 is vertically alined with an actuating projection 154 rising near said magazine. Upon the descent of the head for engagement with the upper piece F, the projection 150 strikes the projection 154, swinging the valve-plate 152 into position to open communication between the suction-conduit and head, and to close the relief-opening. This causes the air-current established through the head to hold the work-piece firmly against the openings 104, loss of the suction effected through the opening 136 being avoided by its closure by the valve-plate. This relation continues until the descent of the head over the die 27. Then the projection 152 contacts with an actuating projection 156 rising from the frame adjacent to the turret. Again the valve-plate is moved, this time to close the suction-conduit and free the relief-opening. This causes the release of the transferred piece from the head 102, it falling into place upon the die.

Each of the turret-dies 27 has a groove 160 (Figs. 2 and 16) corresponding in form to the sewing rib which is to be molded in the fabric deposited by the transferring mechanism T at stations A and B; and each of the co-operating dies 28 at these stations is provided with a rib or projection 161 (Fig. 1), arranged to enter the depressions when the upper dies are forced down by the crank mechanisms 40 and to cause the formation of the ribs. To increase the rigidity of the rib and to make it conform more perfectly to the dies, heat is applied to the fabric during the molding operation. For the accomplishment of this, the lower dies are provided with electric heating units 162 (Figs. 2 and 3) inserted in recesses in the turret adjacent to said dies. They are supplied with current in parallel through conductors 164, each side of the circuit terminating at a contact 166 carried at the periphery of the turret and separated from each other by 180 degrees. To these contacts current is delivered through brushes 168. This supply, because of the extent of the contacts 166, is effective only while the turret is at rest, this time being sufficient to properly heat the dies. At stations A and B, the heat imparted directly to the dies 27, 27 and indirectly to the co-operating dies 28, 28 is effective to set the form of the rib which the dies produce; and at stations C and D, it acts to promptly dry the adhesive, applied as is hereinafter described.

After the rib-molding operation and elevation of the dies 28, the rotation of the turret carries the dies 27 with the formed blanks upon them from stations A and B to stations C and D. The holding and feeding means for the leather blanks L (Figs. 10 to 13, inclusive) include a table 170 fixed to the main frame at each of the stations C and D, the

top of each table lying in a horizontal plane somewhat above the working face of the die 27 at the station. The blanks L are carried in a stack upon the table, vertically alined with one another at the side toward the turret by bars 172, 172 carried by a horizontal bar 174, which is mounted upon a bracket 175 secured to the main frame and furnishing at its top the table 170. Each of the bars 172 has at its lower end a yieldable portion 176 pivoted to the body of the bar and held normally in alinement therewith by a spring 178. Between the lower end of each portion 176 and the table is a space sufficient to permit the passage of the normal blank which is to be delivered, while retaining the succeeding blanks of the stack. The yield of the portions 176 avoids the catching upon the bars and holding against the feeding action, of blanks somewhat thicker than the normal, the portions 176 swinging outwardly to permit their passage. At the opposite or outer side of each magazine are vertical bars 180, 180, with their lower ends extending close to the table and being mounted upon a carriage 182 movable in ways in said table to permit the adjustment of the magazine to varying widths of soles. The ends of the soles are positioned by vertical bars 184 mounted to swing upon bell-crank-levers 186 fulcrumed upon the table 170. To maintain the flat inner faces of the bars 184 parallel to each other for effective contact with the square ends of the blanks L, links 188 are pivoted to them and to the table. I provide for the simultaneous adjustment of the bars 180 and 184 in the proper relation as the soles to be received by the magazine vary in width and length, by joining the carriage 182 to each of the bars 184 through lever-systems 187 so proportioned as to give the desired relative movement. Travel of the carriage is effected through a projection 189 depending from it and entering a cam-groove in the periphery of a cylinder 190 secured to a shaft 192 journaled in the bracket 175 beneath the table. The shaft 192 is geared at 194 to an inclined shaft 196 rotatable in the bracket. At the upper end of the shaft 196, convenient for the operator of the machine, is a crank 198 having a spring-latch 200 arranged for engagement with any one of a circular series of openings 202 formed in a plate 204, which extends from the outer vertical face of the bracket. Size designations appear upon the plate, corresponding to the settings of the magazine-bars by the crank and actuating connections which give the correct dimensions of the magazines.

The bottom blanks of the stack in each of the leather-portion magazines are advanced one by one beneath the bar-ends 176 across the table 170 by feed-slides 206, two of which are associated with each of these magazines.

Each slide is movable in a slot in the table and supports a contact-finger 208 (Fig. 12) pivoted at 210 upon the slide and held with its work-engaging end yieldably raised by a spring 212 seated in a recess in the slide. A stop-screw 214 at the opposite side of the pivot from the spring adjustably limits this movement. At the inner end of the finger is an inclined surface 216, the inner and outer extremities of which are respectively normally below and above the lower face of the bottom blank in the magazine. The surface 216 terminates at its outer end in a vertical wall 218, the height of which is somewhat less than the minimum thickness of the blanks to be fed. As the fingers are carried by their slide across the table, the lower portions of the inclines 216 lie always below the supporting surface of the table, and therefore below the bottom of the lowest blank in the magazine; and as the surfaces 216 engage the under face of the blank, they yield until the vertical surface 218 contacts with the edge of the blank. This, in the continued movement, is forced from beneath the stack over the table from the magazine. The fingers thus accommodate themselves unfailingly to irregularities in the sole-edges. Each slide is reciprocated to produce this feeding movement by an arm 220 (Fig. 13) forked to engage a block 222 arranged to turn upon the slide, the lower end of the arm being fixed to a shaft 224 journaled in the bracket 175 beneath the table. Fast on the shaft 224 is an arm 226 joined by a connecting-rod 228 to a link 230 (Fig. 14) suspended upon the bracket and having a projection 232 entering a cam-groove in a disk 234 fixed upon a shaft 236 journaled in the frame. The shafts 236 at stations C and D are connected by bevel-gearing 238 (Fig. 13), while spiral gearing 240 joins one of the shafts 236 to an inclined shaft 242 actuated through bevel-gearing 244 from the shaft 122 (Fig. 4). To allow the reciprocation of the fingers to be discontinued and thus render the feeder ineffective while the machine is still in operation, a pin 246 uniting the arm 226 and connecting-rod 228 may be rotatable in the arm and arranged to be fixed in different angular positions. Its cylindrical portion enters a notch in the connecting-rod to produce the feeding effect, while a cam-portion 248 may, when desired, be turned into engagement with the under side of the connecting-rod, thus lifting the latter to separate the depression from the pin and disconnect the arm 226. At this time, the generally horizontal under edge of the connecting-rod rides upon the cam-portion. Thus the feed of the blanks L may be discontinued, similarly to the blanks F.

The fingers 208, in their reciprocation, feed the lower blanks at stations C and D, forward across the tables 170, being here shown as delivering to an apparatus for ap-

plying to the leather portions a cement or other adhesive. The delivery-surface is horizontally alined with the bite of a lower applying roll 250 (Figs. 13 and 15) journaled horizontally in the upper part of the bracket 175 and an upper pressure-roll 252 rotatable upon opposite levers 254, 254 fulcrumed just above the table. To the vertical arms of these levers, which are of the bell-crank type, are attached springs 256 drawing the arms against stop-screws 258. These screws furnish an adjustment whereby the normal separation between the applying and pressure-rolls may be varied, the upper roll also yielding to accommodate the pressure to work of different thicknesses. Beneath this pair of rolls is a platform 260 for the support of a removable cement-receptacle having two sections 262 and 264. In the former operates a feed-roll 266, journaled in opposite bell-crank-levers 268, 268, each having an arm held by a spring 270 against a stop-screw 272. Adjustment of these screws raises and lowers the feed-roll, so that it may be caused to deliver different quantities of cement to the applying roll. The receptacle-section 264 communicates with the associated section through an opening 274 furnishing a barometric feed, which maintains the cement in the section 262 at a constant level. The section 262 of the receptacle fits against a casing-section 274 fastened upon the bracket 175, and the supporting platform of the receptacle is arranged for movement to force the receptacle into contact with the casing-section, thus partly sealing it to reduce evaporation of the solvent, or to lower it to facilitate removal. For this purpose, the platform is carried upon four bell-crank-levers 276 fulcrumed upon the bracket and joined by pairs of links 278 (Fig. 10). These, in turn, are linked at 280 to a bell-crank-lever 282 fulcrumed below and at one side of the receptacle. Pivoted upon the outer arm of the lever 282 is a handle 284 having a latch-arm 286. The arm engages a projection 288 upon the frame, this holding the platform 260 in its normal raised position. Swinging the handle 284 upwardly releases the latch, permitting the platform and receptacle to fall into a position at which the latter may readily be removed. To rotate the rolls of the applying apparatus, the shaft 236 is joined by sprocket-gearing 290 to a short shaft 292, from which a chain 294 of spur-gearing drives the rolls in the directions indicated by the arrows in Fig. 13.

When the coated blank emerges from the applying apparatus at each of the stations C and D, it is received by a transferring mechanism U, which delivers it to the particular die 27 which is at the station. This transferring mechanism is so organized as to position blanks of different sizes in correct relation upon the formed fabric portion borne

by the die. Just below the bite of each pair of rolls 250, 252, and arranged to reciprocate from a point adjacent to said rolls into proximity with the die 27 resting at the station at which these rolls are located, is a carrier 300 (Figs. 13 and 16) consisting of a plate, upon which are secured contact-strips 302. These strips offer reduced edges, which disturb but little of the coating upon the blanks as said blanks are passed over them. Arms 304, 304 are attached to a horizontal shaft 306 turning below the table 170 and pivotally support the carrier, the latter being maintained horizontal during its reciprocation by a link 308 pivoted at 310 upon the frame, or other point fixed relatively to the link, and having pin-and-slot connections at 312, 312 with one of the arms 304 and with a lug 314 depending from the carrier. The reciprocation of the carrier through a constant distance, from a receiving to a delivering position and the reverse, is effected by oscillating the shaft 306 through an arm 316 fast thereon, and having a projection 318 entering a cam-groove in the inner face of a disk 320 secured to the shaft 236. Flexible supports, in the form of leaf-springs 322, of which two are illustrated, project forwardly from the carrier between the strips 302, preferably extending over the die 27, in the forward position of the carrier, at least as far as the groove 160. These supports, when the sole-portion L is finally delivered to the die, prevent its forward edge from catching in the groove in the formed canvas and thus interfering with its correct placing. The spring material of which they are made allows them to yield upon contact with the die as the carrier 300 is swung forward and down toward said die.

The blank is pushed from its carrier 300 upon the die by delivering and positioning fingers 324, 324 curved toward the rear and then somewhat forward in the direction of the die. Each finger is fixed to a short horizontal shaft 326 rotatable at the upper extremity of an arm 328 free to turn about a shaft 330 journaled parallel to the carrier-supporting shaft 306. Fixed to the shaft 330, adjacent to each arm 328, is an actuating arm 332. This exerts a positive effect upon the arm 328 in one direction by contact of an overhanging portion 334. The arm 328 is yieldable in its travel in the opposite direction against the tension of a spring 336, which is connected at its opposite extremities to the arms 328 and 332. This arrangement permits a difference in the extent of movement of the respective pairs of arms, so that after the fingers have come to rest, the forward movement of the actuating arms may continue. The shaft 330 and arms 332 are oscillated by an arm 338 secured to the shaft and provided with a projection 340 entering a cam-groove in the outer face of the disk 320.

The extent to which the two fingers associated with the carrier 300 are moved toward the die is controlled by stop-disks or cams 342 set by the crank 198 simultaneously with the 5 magazine-bars and providing for the same size-changes. Each stop-disk has five steps, one for each of the crank-retaining openings 202, and the two disks are fixed upon opposite ends of a shaft 344. Bevel-gearing 346 10 connects the shaft 344 to the shaft 196 carrying the crank 198. With the stop-surfaces of the disks contact screws 348 threaded through arms 350 formed with the arms 328. When the operator sets the cranks 198 at positions C and D for a change in the size of 15 the blanks to be fed from the magazines, a like setting of the disks is effected, so the extent of movement of the delivering fingers 324, 324 is similarly altered to symmetrically place the blanks upon the dies 27. Adjustment of the screws 348 provides for different 20 travel of the fingers at the heel and toe-portions of the dies.

The fingers 324 not only travel with the 25 carriers in a movement of translation by virtue of the oscillation of the arms 328 and 332, but are also turned by the shafts 326 to more effectively deliver the blanks from the carriers upon the dies. The shafts 326 are 30 mounted to rotate together, while being relatively movable transversely of the carrier, by a shaft-section 352 (Fig. 11) including universal joints 354. Attached to one of the 35 pair of shafts 326 is an arm 356, to which is articulated a link 358 guided by a slot in it which receives a projection 360 extending from the frame. A spring 362, joining the projection and link, exerts its force to turn the fingers into a forward or delivering position. A pin 364, projecting from the outer 40 side of the arm 356, by contact with the link 358, limits the movement of the fingers in this direction. When the carrier is positioned adjacent to the cementing apparatus for the purpose of receiving the coated blank therefrom, the fingers are moved outwardly and upwardly, to leave a space between them and the carrier into which the blank may be delivered by the rolls 250 and 252. This is 45 accomplished by a projection 366 (Fig. 16) from the inner side of the arm 356, which projection engages, in the location of the carrier just mentioned, a contact member 368 fixed upon the frame. The position assumed by the fingers under the influence of this contact device is best illustrated in Fig. 13 of the drawings.

A leather blank L, having been fed from its magazine by the fingers 208 to the rolls 250, 252 and coated thereby upon its lower side, is delivered by said rolls to the carrier beneath the raised fingers 324. A cam of the disk 320 thereupon swings the carrier toward the die until the spring-supports 322 project over it. At the same time, the fingers 324 travel with

and over the carrier, forcing the blank from the latter upon the die. The carrier then retreats, the fingers temporarily retaining the blank to avoid disturbance of its position when the spring-supports are withdrawn, and finally leave it correctly positioned for the 70 assembling operation.

The leather blanks having been placed upon the fabric portions carried by the dies 27, the dies 29 descend under the influence of the crank mechanisms 40 to force the two layers 75 together. For this purpose, each of the dies 29 has a horizontal pressure-surface corresponding to the like surface of the dies 27. The setting of the adhesive is facilitated by heating of the dies 27 through the electric units 162. If it is desired to produce in the work openings spaced from one another in the heel-portions of the leather blanks for locating the completed soles in succeeding shoe-making operations, these openings may be 80 formed at positions C and D by punches 370 (Figs. 17 and 20) carried by the dies 27 and operating against anvils 372 mounted upon the dies 29. The anvils are preferably in the 85 form of plungers of relatively soft metal movable in casings 374 secured side by side upon the upper face of each of the dies 29. Within the casings are springs 376 interposed between the tops of the plungers and the lower 90 extremities of screws 378 threaded into the casings. These springs yieldably hold the anvils to receive the cutting action of the punches, and the resistance to displacement of the anvils may be adjusted by change in 95 the vertical positions of the screws.

For the release of the completed sole from the groove in each die 27 after the co-operating die 29 has been raised, the latter has, fulcrumed for horizontal movement and transversely alined at its toe and heel-portions, respectively, where it extends beyond the edge of the die 27, lifting members 380, 380 and 382, 382, respectively (Figs. 17, 18 and 19). These pairs of members are arranged for movement beneath the edge of the sole-material overhanging the periphery of the die 27. They are shown in the form of bell-crank-levers, the long arms of which are arranged to engage the sole, while shorter arms of each pair extend toward each other. To each lever is articulated a rod 384, those of the members 380 passing through openings in projections from opposite sides of a bell-crank-lever 386 fulcrumed for oscillation in a vertical plane upon a bracket carried by the die 29. The rods of the members 382 are similarly related to a lever 388 carried by the opposite end of the die. Springs 390, surrounding the rods between the lever-projections and nuts 392 threaded upon the outer extremities of the rods, permit the members 380 and 382 to yield independently when they are moved against the peripheries of the corresponding dies 27 in their sole-engaging positions. A link 394

connects arms 395 upon the fulcra of the levers 386 and 388, to cause them to move together. Joining the link and the upper portion of the die 29 is a spring 396, by which the outward or work-dropping position of the members is normally maintained.

Pivoted to the lever 386 and extending vertically through an opening in a bracket 400 secured to the upper portion of the frame 26 10 above the turret, is a link 398. Threaded upon the link above the bracket is a nut 402, which, by its contact with said bracket when the die 29 is lowered, swings the levers 386 and 388 to carry the members 380 and 382 inwardly into their work-engaging relation toward the die. The time of the engaging movement may be altered by adjusting the nut 402 upon the link. The members are temporarily held in this position against the 20 tension of the spring 396 by a latch 404 (Fig. 18) movable in a horizontal casing 405 upon the end of the die 29 adjacent to the lever 386, and forced by a spring within the casing into the path of said lever. As the die 25 29 rises, carrying the completed sole with it resting upon the members 380, 382, the latch 404 is drawn back to release the members and free the sole by a vertical contact-bar 406 clamped upon the bracket 400 just at the inner side of the link 398. The lower end of this bar is beveled, and, in the elevation of the die, receives contact of the head of the latch, withdrawing it to release the lever 386. This permits the spring 396 to act, drawing 30 the members out much more rapidly than they are moved into their engaging relation, so that the freed sole drops back loosely upon the die 27 immediately after the die 29 leaves it. This occurs at both stations C 35 and D.

The soles having thus been released from the grooves in the dies 27, they are to be discharged from the machine, the left soles completed at station C being kept separate from 40 the right produced at station D. Between stations C and D is mounted upon the main frame a spring ejector 410 (Fig. 2), and between stations D and A, a similar device 412. Each of these has a contact-end lying in the path of the dies 27, and so related that it will engage the detached soles carried by them. To move the ejectors against the soles, they are tensioned and released by the wiping engagement of actuating projections 414 rising 45 vertically from the turret at the inner sides of the dies 27, and so located radially that, as they pass the springs, they will bend them back and free them to strike and throw the soles outward, clear of the machine. Each 50 projection has secured to it a light spring supporting member 416 (Figs. 11 and 18). This, extending toward the associated die, serves to hold the inner edge of the soles raised and dropped by the members 380 and 382, guarding said soles against falling in 55

positions in which they will not be engaged by the ejecting springs. To avoid the actuation of the ejector 410, when the right dies rather than the left are passing, it is pivoted at 418 for vertical movement, and has an arm 420, which contacts with the upper cam-edges of bars 422 fixed at opposite sides of the turret and associated with the right dies in such a relation circumferentially of the turret that the arm 420 will contact with one of them just as the projections 414 opposite said right dies are passing the springs 410. This ejector will therefore be raised and not actuated, being effective only when the projection belonging to the die upon which it is to act reaches it.

Considering the driving system of the machine, the motor 30 is shown as belted to a counter-shaft 430 (Fig. 4) journaled at the bottom of the frame and having fixed to it a fly-wheel 432. Current is delivered to the motor through a switch enclosed in a casing 434 (Fig. 1), and opened or closed by connections at 436 to a hand-lever 438 pivoted upon the frame. A like hand-lever at the opposite side of the machine is joined to 438 by a lever-and-link system 440. Simultaneously with the opening and closing of the motor-circuit, a brake-band 442 (Fig. 5) is respectively drawn against or released from the fly-wheel by a link 444 articulated to the lever 438 and operating the brake-band through toggles 446 and 448. Therefore, when the lever 438 is raised to close the switch, the brake-band is simultaneously released to free the fly-wheel, and when said lever is lowered, the brake is applied to the fly-wheel. A treadle 450 may be included in the lever-system, connecting through the toggle 448 with the band 442, so that the brake may be applied independently of the movement of the hand-lever. Worm reducing gearing 452 transmits power from the countershaft to a shaft 454 rotatable about a vertical axis in the frame, and to which is secured the driving member of the clutch mechanism 32. The upper driven section of the clutch mechanism is geared to the turret at 36, while the lower driven section which rotates the crank mechanisms 40, cam mechanism 34 and feed-shafts 118 and 242 through the time-controlling mechanism X, is connected by spiral gearing 458 to a sleeve 460 rotatable about the shaft 122. The purpose of this mechanism X is to vary the duration of the operation of the dies upon the work. As is best shown in Figs. 21 and 22, the sleeve 460 has clamped upon it an internally toothed disk 462 of a clutch of the Bliss type, the other disk 464 of which is fast upon the shaft 122 and carries a rotatable key 466 for engagement with the teeth. A spring 468, extending from an inner arm of the key to the outer face of the disk 464, exerts a force tending to so rotate the key that it will come into 115 120 125 130

the path of the teeth to connect the driving member 462 with the driven member 464. The key is normally held disengaged from the disk 462, so that the disk 464 and shaft 122 are at rest, by a stop-bar 469 arranged to move into the path along which travels a tail 471 of the key. The stop-bar projects from one end of a shaft 470 rotatable within a sleeve 472 (Fig. 23) journaled in a bracket 474 mounted upon the frame. At the opposite extremity of the shaft 470 from the arm is a head 476 having a peripheral projection 478 (Fig. 21). A spring 480, joining the stop-bar 469 to the bracket, draws a projection 482 upon the stop-bar into engagement with the bracket to determine the position of the end of the bar in the path of the key-portion 471. Extending radially from a sleeve 484 turning upon the sleeve 472 is an arm 486 having a screw or other projection 488, which may be inserted in any one of a series of openings 490 formed in a plate 492 rising from the bracket parallel to the arm. Engagement of the projection with one or another of the openings alters the angular relation of a stop-projection 494 lying at the inner side of the arm 486 and serving to variably determine the normal position of a timing disk 496 fixed to the outer extremity of the sleeve 472. A helical spring 498 surrounding the sleeve 484 is secured at 500 and 502 to the arm 486 and the disk 496, respectively, and acts to draw a projection 504 at the inner side of the disk toward the stop-projection 494. Upon the outer face of the disk 496 is an actuating projection 506, which, when said disk is turned in an anti-clockwise direction, as viewed in Fig. 21 of the drawings, will strike the projection 478 upon the head 476, turning the shaft 470 to raise the stop-bar 469. This releases the key 466, allowing it to turn into engagement with the traveling teeth of the disk 462 to drive the shaft 122. Upon the periphery of the disk 496 are two sets of ratchet-teeth 508 and 510. With the first of these co-operates a pawl 512 yieldable upon the generally vertical arm of a bell-crank-lever 514 fixed to a shaft 516 rotatable in the bracket adjacent to the shaft 470. A horizontal arm of the lever 514 has a projection 518 operating in a cam-groove in the outer face of the disk 462. This groove is so formed that, in the continuous rotation of the disk, the lever is constantly oscillated, to move the pawl 512 into engagement with the teeth 508. A retaining detent 520 for engagement with the set of ratchet-teeth 510 terminates one arm of a bell-crank-lever 522 mounted to turn about the shaft 516, the other arm of which lever carries a roll 524 for contact with the periphery of the clutch-disk 464. A spring 526 acts to simultaneously draw the detent against the ratchet-teeth and the roll into contact with the disk. For the greater portion of the arc of contact between the roll and disk, the circular contour of the latter is unbroken. This so positions the lever 522 that the detent 520 is out of co-operation with the ratchet-teeth 510. During this period, the pawl 512, in its oscillation, imparts a corresponding idle oscillation to the disk 496. A relatively small peripheral portion of the disk 464 is depressed, as appears at 528 in Fig. 21. When the roll 524 arrives at this depression, the spring 526 draws the detent into engagement with the ratchet-teeth. Now when the pawl 512 acts upon the disk, each oscillation causes said disk to advance a step, this being held by the detent. The movement continues until the disk-projection 506 strikes the head-projection 478, lifting the stop-bar 469 to release the clutch-key and produce rotation of the shaft 122, as previously described. The roll 524 then rides out of the depression, releasing the disk 496 from the detent, and permitting the spring 498 to act to return the projection 506 to its position against the projection 494 upon the adjusting arm. Since, however, the portion 471 of the key has left the stop-bar, rotation of the disk 464 and the driven shaft continues, during this interval the pawl producing its idle oscillating movement of the timing disk. After the driving disk 462 has made one turn, the key arrives at the stop-bar 469 to release the disk 464 and stop the shaft 122, while the depression 528 also reaches the roll 524 to initiate another timing action of the mechanism. It will be seen that the length of the interval during which the clutch-elements are disconnected and the shaft 122 is at rest, depends upon the position of the arm 486, since this determines the initial position of the projection 504 and the arc through which the projection 506 must move to release the clutch-key from the stop-bar. The manner in which the stopping and starting of the shaft 122 by the mechanism X controls the movement of the work and the time of application of pressure by the dies will be hereinafter described.

A brief outline of the general operation of the machine will now be given. Let it be assumed that, at the completion of a cycle, the turret is at rest, bearing upon the dies 27, at stations A and B, canvas blanks F, in which the sewing ribs have been molded, while completed soles have been produced upon the dies 27 at stations C and D. At the beginning of the succeeding cycle, the cam mechanism 34 causes the engagement of the upper section of the clutch mechanism 32, the lower section being disengaged. This upper section drives the turret through the gearing 36, so that it moves through 180 degrees, carrying one of the dies 27 from each of the stations A and B to the stations C and D, and causing those at stations C and D to move to stations A and B. From the last-mentioned dies, the finished soles are thrown off.

by the ejecting members 410 and 412. The turret having been stopped by the cam-control, the clutch mechanism is shifted to disengage its upper section and engage the lower section. At this time, the disks 462 and 464 are clutched together by the key 466, and the shaft 122 is in rotation. The first action is for a transfer mechanism T to engage a canvas blank F from the stack in the magazine at each of the stations A and B, convey the blanks over the dies 27 at those stations, and release them so that they are left upon the dies. Concurrently, the reciprocatory feed-fingers 208, associated with the magazines at stations C and D, project the lower blank L from each magazine between the cementing rolls 250 and 252, so that the under side is coated and it is deposited upon a carrier 300. The carriers at stations C and D then transfer the blanks to the dies 27 bearing the canvas blanks formed in the previous cycle of the machine, to which formed blanks the blanks L are delivered by the oscillatory fingers 324 from the carriers. The travel of the blanks L from each magazine is in a direct path radial of the turret. The transferring mechanisms being clear of the dies, the crank mechanisms 40 cause the upper dies 28 and 29 at all the stations to descend simultaneously. At stations A and B, the ribbed dies 28 act to mold the canvas blanks to produce their sewing ribs. At stations C and D, the dies 29 press the cemented leather blanks L upon the already formed canvas blanks, and by the punches 370 produce the locating openings to complete the soles. At stations A and B, the form imparted to the canvas is made more perfect, and at stations C and D, the drying of the cement is hastened by the heat transmitted to the dies from the electric units 162. As the end of the action of the dies under the control of the cam mechanism 34 approaches, the clutch-disk 464, in its rotation, brings the key 466 to a point at which it is disengaged from the disk 462 by contact with the bar 469, while the roll 524 enters the depression 528 in the disk 464. This stops the shaft 122 and starts the action of the time-controlling mechanism X, which determines the interval of rest of said shaft, and therefore of the cam mechanism 34 and the crank mechanisms 40 governed thereby. In this manner, the interval of pressure applied by the dies 28 and 29 to the work may be prolonged to an amount varying from a minimum, when the arm 486 is at its extreme position to the left, as seen in Fig. 21 of the drawings, to the maximum, when it is at the opposite end of the series of openings 490. In the first instance, it takes but few oscillations of the pawl 512 to bring the actuating projection 506 against the projection 478 to release the clutch-key from the stop-bar. At the other extreme, the full movement of the disk 496 is permitted, since the

pawl 512 may act upon the entire series of ratchet-teeth 508, and the time of rest of the shaft 122 and the prolongation of pressure is at a maximum. Between the two limits, by adjustment of the arm 486, the duration of pressure may be chosen which will give the best results, considering the material which is under treatment. Whatever may be the time thus chosen to complete the forming and assembling of the soles, the time-intervals of the other mechanisms, as those which cause the work-feeding and turret-rotation, remain unchanged, so that no ineffective delay is introduced into the cycle. When the shaft 122 and cam mechanism again start in rotation, the latter operates to disengage the lower section of the clutch mechanism 32, terminating the cycle. The soles completed at stations C and D are discharged from the machine by the ejectors 410 and 412, at the beginning of the succeeding cycle, into receptacles placed beside it.

Having described my invention, what I claim as new and desire to secure by Letters Patent of the United States is:

1. In a machine of the class described, means for operating upon work-portions, driving means therefor, a holder for work-portions, transferring means for delivering work-portions to the operating means, means in constant engagement with the work-portions in the holder and movable under the influence of the driving means to bring the portion to be transferred into the field of action of the transferring means and to provide an excess of travel toward said transferring means, and means arranged to render the positioning means ineffective independently of the driving means.

2. In a machine for making soles, means for operating upon sole-portions, driving means therefor, a magazine including a platform for supporting sole-portions, transferring means movable between the platform and operating means, means for elevating the platform, said elevating means being arranged to force the sole-portions against the transferring means, and means arranged to render the elevating means ineffective while the action of the operating means continues.

3. In a machine of the class described, means for operating upon work-portions, driving means therefor, a holder for work-portions, a movable feeder co-operating with the holder, connections to the driving means for operating the feeder, said connections including an adjustable member rotatable to connect or disconnect the driving means and feeder, and means for fixing the member in its adjusted position.

4. In a machine of the class described, means for operating upon work-portions, driving means therefor, a holder for work-portions, a movable feeder co-operating with the holder, and connections to the driving

means for operating the feeder, said connections including a link and a pin provided with a cam-surface rotatable to act upon the link and break the connections.

5. In a machine of the class described, a holder for work-portions, means for operating upon the work-portions, means contacting with work-portions in the holder and being movable to advance them to the operating means, a movable carrier upon which the operating means delivers the work-portions, and other operating means receiving from the carrier.

6. In a machine of the class described, a magazine for work-portions, coating mechanism, means contacting with work-portions in the magazine for advancing said work-portions directly therefrom to the coating mechanism, a movable carrier upon which the coating mechanism deposits the coated portions, and die mechanism receiving from the carrier.

7. In a machine of the class described, a magazine for work-portions, coating mechanism including a pair of rotatable rolls, a feeder delivering from the magazine to the rolls, die mechanism, and a carrier upon which the rolls deposit the coated portions and being movable between said rolls and the die mechanism.

8. The combination with a rotatable turret, of operating means carried thereby, a holder for work-portions situated adjacent to the turret, operating mechanism interposed between the holder and turret, and means arranged to advance the work radially of the turret from the holder through the operating mechanism to the operating means.

9. In a machine for making soles, the combination with a rotatable turret, of a die carried thereby, a magazine for sole-portions situated adjacent to the turret, coating mechanism interposed between the magazine and turret, and means arranged to advance sole-portion radially of the turret from the magazine through the coating mechanism to the die.

10. The combination with operating means, of delivering means movable toward the operating means and including a carrying member and a positioning member, and means arranged to control the extent of movement of the positioning member independently of the carrying member in accordance with the size of the object operated upon.

11. The combination with a die, of a carrier and an oscillatory finger both movable into proximity with the die, and means arranged to adjustably limit the extent of oscillation of the finger over the carrier toward the die.

12. In a machine for making soles, means for operating upon sole-portions, a member movable to deliver sole-portions to the operating means, a stop with which the delivering member contacts in its movement, and means

arranged to vary the position of the stop in accordance with the size of the sole to be made.

13. The combination with operating means, of a lever fulcrumed adjacent to the operating means, means for oscillating the lever, a delivering member movable upon the lever, and a rotatable member having differently related stop-surfaces with which the lever may contact and arranged to variably position the lever in preparation for the movement of the delivering member thereon.

14. The combination with operating means, of a delivering member movable toward and from the operating means and having an independent movement of oscillation into and out of delivering position, means acting to hold the delivering member normally in delivering position, and means for moving the delivering member out of delivering position when at its outward limit of movement from the operating means.

15. The combination with a die, of a lever fulcrumed adjacent to the die, means for oscillating the lever, a delivering finger pivoted upon the lever, contact means arranged to swing the finger upon movement of the lever in one direction, and means arranged to swing the finger oppositely upon movement of the lever in the other direction.

16. The combination with operating means, of a plurality of delivering members therefor respectively movable through different distances toward the operating means, and means arranged to independently determine the extent of such movements in accordance with the size of the delivered object.

17. The combination with a die for shoe-soles, of a plurality of delivering members movable independently of one another through different distances at the heel and toe-portions of the die.

18. The combination with operating means, of a plurality of delivering members therefor having independently of one another movement of translation toward and from the operating means, and means for turning said members simultaneously.

19. The combination with operating means, of two levers fulcrumed adjacent to the operating means, means for oscillating the levers, shafting connecting the levers, and delivering fingers carried by the shafting.

20. The combination with operating means, of two levers fulcrumed adjacent to the operating means, means for oscillating the levers independently of each other, a shaft journaled in each lever, a delivering finger carried by each shaft, and connections between the shafts to cause them to turn together.

21. The combination with operating means, of a movable carrier for work-
130

- tions to be operated upon, means for moving the carrier between receiving and delivering positions, and a delivering member movable with the carrier and in the direction of its 5 movement toward the operating means.
22. The combination with operating means, of a movable carrier for work-portions to be operated upon, means for moving the carrier between receiving and delivering 10 positions, a delivering member associated with the carrier, means for moving the member to facilitate reception by the carrier of the work-portions, and means for moving the member with the carrier and across said 15 carrier to cause the delivery of the work-portions.
23. The combination with operating means, of a movable carrier for work-portions to be operated upon, means for moving 20 the carrier between receiving and delivering positions, a delivering member associated with the carrier, means for moving the carrier through a constant distance toward the operating means, means for moving the delivering member with the carrier, and means arranged to vary the extent of movement of the delivering member toward the operating means.
24. In a machine for making soles, a die, 25 coating mechanism, a carrier upon which a sole-portion is delivered by the coating mechanism, and means for moving the carrier between the coating mechanism and die.
25. In a machine for making soles, a die, 30 coating mechanism, a carrier upon which a sole-portion is delivered by the coating mechanism, and means for moving the carrier between the coating mechanism and die, and means for pushing the sole-portion from the 35 carrier upon the die.
26. In a machine for making soles, a die, coating mechanism, a carrier-plate upon which a sole-portion is delivered by the coating mechanism, and a finger movable with 40 the carrier-plate and across said carrier-plate to deliver to the die.
27. In a machine for making soles, a die, coating mechanism, a carrier-plate having reduced contact-strips upon which a sole-portion is delivered by the coating mechanism, and a finger movable with the carrier-plate between the contact-strips and across said carrier-plate to deliver the sole-portion 45 to the die.
28. In a machine for making soles, a die, a carrier movable to deliver to the die, and flexible supports extending from the carrier toward the die.
29. In a machine for making soles, a die, a carrier movable to deliver to the die, and flexible supports extending from the carrier over the die in the delivering position.
30. The combination with operating means, of means for supplying work-portions, levers oscillating between the supply- 50
- ing and operating means, a carrier-plate pivoted upon the levers, and means for maintaining the carrier-plate substantially horizontal during the movement of the levers.
31. The combination with operating means, of means for supplying work-portions, levers oscillating between the supplying and operating means, a carrier-plate pivoted upon the levers, and a link joining the carrier-plate to a relatively fixed point. 70
32. The combination with operating means, of means for supplying work-portions, levers oscillating between the supplying and operating means, a carrier-plate mounted upon the levers, levers fulcrumed adjacent to the carrier-levers and having delivering fingers situated above the carrier-plate, and means for oscillating the finger-levers. 75
33. The combination with operating means, of means for supplying work-portions, levers oscillating between the supplying and operating means, a carrier-plate mounted upon the levers, levers fulcrumed adjacent to the carrier-levers and having yieldable sections, delivering fingers mounted upon the yieldable sections, adjustable stops for said sections, and means for oscillating the finger-levers. 80
34. The combination with operating means, of an adjustable work-positioning member normally fixed against movement, an adjustable member movable to deliver work from the positioning member to the operating means, and means arranged to adjust simultaneously the positioning member and delivering member. 85
35. The combination with operating means, of a holder variable in size to receive different sized work-portions, means movable through varying distances for transferring work-portions between the holder and operating means, and means arranged to adjust simultaneously the size of the holder and the travel of the transferring means. 90
36. In a machine for making soles, means for operating upon sole-portions, a magazine for sole-portions, a traveling member delivering from said magazine to the operating means, and means arranged to vary the size of the magazine and the travel of the delivering member to correspond to the size of the soles to be made. 100
37. In a machine for making soles, a die, a magazine having independently movable positioning members for contact with the heels and toes of sole-portions, traveling members respectively engaging the heels and toes of such portions for their delivery to the die, independent stops for adjustably limiting the travel of the heel and toe-engaging members, and a member arranged to adjust the positioning members and stops and being common to all. 110
38. In a machine for making soles, a die, 120
- 65

- 5 a magazine having a movable positioning member for sole-portions, a member for delivering the sole-portions to the die, a movable stop for the delivering member, a setting member, and connections between said setting member and the positioning member and stop. 70
- 10 39. In a machine for making soles, a die, a magazine having movable positioning members for sole-portions, members for delivering the sole-portions to the die, movable stops for the delivering members, a setting member, means associated with the setting member for indicating the sizes of the soles to be made, and connections between 75
- 15 said setting member and the positioning and delivering members, said connections being constructed and arranged to move the positioning members and stops differently for 80
- 20 each size-indication.
- 25 40. The combination with upper and lower pressure members, of a member movably mounted upon the upper pressure member and movable into engagement with the work to lift it from the lower pressure member, and means for moving the lifting member upon the upper pressure member. 85
- 30 41. The combination with opposite pressure members movable relatively to each other, the outer edge of one of which members lies within the edge of the work, of a member movably mounted upon one of the pressure members and movable toward the other pressure member and into engagement 90
- 35 with the overhanging edge of the work and then away from said other pressure member to separate the work therefrom. 95
- 40 42. The combination with a die having a groove, of a co-operating die movable toward and from the grooved die, a work-releasing member mounted upon said movable die, and means acting upon the approach of the die to carry the releasing members toward the grooved die for engagement with 100
- 45 the work. 105
- 50 43. In a machine for making soles, a pair of cooperating dies one of which extends beyond the edge of the other, means for reciprocating such overhanging die, and a sole-engaging member mounted upon the overhanging die and movable into engagement with the associated die. 110
- 55 44. In a machine for making soles, a pair of cooperating dies one of which is movable toward and from the other and provided with a projection arranged to enter a groove in its companion, a pair of members mounted upon the movable die and arranged to engage a sole retained by the groove of the associated die, and means fixed relatively to the movable die to actuate the sole-engaging members. 115
- 60 45. In a machine for making soles, a pair of cooperating dies one of which is movable toward and from the other, a pair of sole-engaging members mounted upon the mov- 120
- able die and transversely alined with each other at opposite sides of the sole, means fixed relatively to the movable die to actuate the sole-engaging members, and connections between the engaging members and actuating means permitting said engaging members to move through different distances independently of each other. 125
46. In a machine for making soles, a pair of cooperating dies one of which is movable toward and from the other, a pair of sole-releasing members associated with the dies, an actuating lever for the releasing members, and a spring connecting each releasing member to the lever. 130
47. In a machine for making soles, a pair of cooperating dies one of which is movable toward and from the other, a pair of sole-releasing members associated with the dies, an actuating lever for the releasing members, and a link joined to the actuating lever and arranged to contact with an element fixed relatively to the movable die. 135
48. In a machine for making soles, a pair of cooperating dies one of which is movable toward and from the other, a pair of sole-releasing members associated with the dies, an actuating lever for the releasing members, a link joined to the actuating lever and arranged to contact with an element fixed relatively to the movable die, and means arranged to vary the time of contact between the link and fixed element. 140
49. The combination with co-operating pressure members movable relatively to each other, of a work-releasing member associated with the pressure members, means arranged to move the releasing member gradually into engagement with the work, and means arranged to produce a relatively rapid disengagement of the work by the member. 145
50. The combination with co-operating pressure members movable relatively to each other, of a movable work-engaging member associated with the pressure members, means effective in the active movement of the pressure members to move the engaging member, means for temporarily retaining the engaging member in its engaging relation, and means acting upon opposite movement of the pressure members to free the engaging member. 150
- 55 51. In a machine for making soles, a reciprocating die, a co-operating die, a sole-engaging member movable upon the reciprocating die, an element fixed relatively to the reciprocating die and arranged to cause a sole-engaging movement of the member, a latch for temporarily retaining the member in its engaging position, and an element fixed relatively to the reciprocating die and acting to release the latch. 155
- 56 52. In a machine for making soles, a pair of co-operating dies one of which is movable toward and from the other, a pair of sole-releas- 160

ing members associated with the dies, an actuating lever for the releasing members, a latch for the lever, and means fixed relatively to the movable die for actuating the lever and latch.

53. The combination with a die, of a member for lifting work from the die and thereafter dropping said work upon the die, and an ejecting member contacting with the dropped work upon the die.

54. The combination with a traveling die, of a member for lifting work from the die and thereafter dropping said work, a movable ejecting member for contact with the work, and means made active in the travel of the die for moving the ejecting member.

55. The combination with a die, of a member for lifting work from the die and thereafter dropping said work, an ejecting spring for contact with the work, and a member traveling with the die for tensioning and releasing the spring.

56. The combination with a traveling die, of a work-ejecting spring past which the die travels, and a member traveling with the die for tensioning and releasing the spring.

57. The combination with a plurality of traveling dies, of a work-ejecting member individual to each die, and a member acting upon the ejecting member and arranged to prevent the action of said ejecting member upon another die than that to which it belongs.

58. The combination with a plurality of traveling dies, of a movable work-ejecting member individual to a die and past which all the dies travel, and means for moving the ejecting member out of operating position during the travel past it of the dies other than that to which it belongs.

59. In a machine for making soles, a movable turret, a sole-forming die mounted upon the turret, a member movable from the die for lifting a sole therefrom and dropping it, and a member movable adjacent to the path of the die for ejecting contact with the dropped sole.

60. In a machine for making soles, a rotatable turret, a sole-forming die mounted upon the turret, a spring situated adjacent to the turret and arranged to move into contact with a sole upon the die, and a member movable with the turret for tensioning and releasing the spring.

61. In a machine for making soles, a rotatable turret, a plurality of sole-forming dies mounted thereon, a sole-ejecting member movable adjacent to the turret, means for actuating the member during the passage of certain of the dies, and means for moving the member out of the path of the actuating means during the passage of other of the dies.

62. In a machine for making soles, a rotatable turret, right and left sole-forming dies mounted thereon, an ejecting spring for each die mounted adjacent to the turret, one of

said springs being pivoted, a member traveling with each die for tensioning and releasing its spring, and means associated with one of the dies for turning the pivoted spring out of the path of the tensioning member belonging to said die.

63. The combination with a die, of means for lifting work from the die and dropping it thereon, means for ejecting the work from the die, and a spring-support adjacent to the die and arranged to hold the dropped work in position for engagement by the ejecting means.

64. The combination with a die, of means for lifting work from the die and dropping it thereon, means for ejecting the work from the die, and a work-supporting spring situated adjacent to the die.

65. In a machine for making soles, a rotatable turret, a die carried thereby, a sole-ejecting member situated at one side of the die and past which said die travels, and a sole-supporting spring carried by the turret between the die and ejecting member.

66. In a machine for making soles, a rotatable turret, a die carried thereby, a sole-ejecting spring situated at one side of the die and past which said die travels, a tensioning and releasing projection carried by the turret for contact with the ejecting spring, and a sole-supporting spring mounted upon the projection.

67. In a machine for making soles, a die traveling to different operating stations, a die co-operating with the traveling die at one station to form a rib in a sole-portion and punch mechanism acting at another station to produce a locating opening in the sole-portion.

68. In a machine for making soles, a die traveling to different operating stations, a die co-operating with the traveling die at one station to form a rib in a sole-portion, a die at a succeeding station arranged to assemble with the formed portion another sole-portion, and punch mechanism acting in the assembling operation to produce a locating opening in the sole.

69. In a machine for making soles, a die provided with a groove and a punch and traveling to different operating stations, a die co-operating with the traveling die at one station and having a projection arranged to enter the groove to form a rib in a sole-portion, and a die acting at another station to produce a locating opening in the sole-portion, the last-mentioned die being provided with an anvil co-operating with the punch.

70. In an assembling machine, a holder for work-portions, means for operating upon the work-portions, means for transferring the work-portions from the holder to the operating means, driving means common to the transferring and operating means, and means arranged to vary the time of action of the

operating means independently of the length of time during which the transferring means acts.

71. In a machine for making soles, a sole-magazine means for feeding sole-portions from the magazine for operations upon them, means for exerting pressure upon the sole-portions, and means arranged to vary the duration of pressure independently of the length of time of advance from the magazine.

72. The combination with means for applying pressure to the work, of means rotatable to control the application of pressure, and means for stopping the controlling means while pressure is being applied.

73. The combination with means for applying pressure to the work, of means for advancing the work to receive the application of pressure, controlling means movable to cause alternately the application of pressure and the advance of the work, and means for stopping the controlling means during the pressure period.

74. In a machine for making soles, pressure mechanism for operating upon interposed sole-portions, transferring mechanism delivering to the pressure mechanism, a motor for driving the machine, and time-controlling mechanism interposed between the motor and the pressure and transferring mechanisms and effective to modify the duration of action of the pressure mechanism only.

75. In a machine for making soles, dies relatively movable to act upon sole-portions, cam mechanism for controlling the action of the dies, and means for periodically stopping the cam mechanism.

76. In a machine for making soles, dies relatively movable to act upon sole-portions, cam mechanism for controlling the action of the dies, means for periodically stopping the cam mechanism, and means arranged to vary the interval during which the cam mechanism is at rest.

77. In a machine for making soles, dies relatively movable to act upon sole-portions, a motor for producing such movement, a clutch interposed between the motor and movable die, and automatic means for periodically disconnecting the clutch at the time of action of the dies upon the sole-portions.

78. In a machine for making soles, dies relatively movable to act upon sole-portions, a motor for producing such movement, a clutch interposed between the motor and movable die, automatic means for periodically disconnecting the clutch, and means arranged to vary the duration of disconnection.

In testimony whereof I have signed my name to this specification.

ERIC A. HOLMGREN.
